ELECTRIC SWITCH

Hugh W. Batcheller, Newton, Mass., assignor to
Standard Mfg. Co., Worcester, Mass., a corpora-
tion of Massachusetts

Application December 18, 1937, Serial No. 180,562

9 Claims. (Cl. 200—153)

This invention relates to an electric switch adapted to be mounted on a wall. While the switch is capable of use in various circuits for various uses, it is more particularly designed for the interior of automobiles to control interior lights such as dome lights and the like. It is an object of the invention to provide a small compact switch, the visible portions of which are an escutcheon and an operating knob, both of which can be made of molded plastic of any desired color. The switch elements are housed within these two members, the only external elements being a pair of binding posts or the like which project from the rear face of the escutcheon for electrical connections.

For a more complete understanding of the invention, reference may be had to the following description of an embodiment thereof, and to the drawing of which

Figure 1 is a front elevation of an electric switch embodying the invention.

Figure 2 is a section on the line 2—2 of Figure 3.

Figure 3 is a section on the line 3—3 of Figure 1.

Figure 4 is a fragmentary elevation similar to Figure 1 but showing the movable parts in a different position.

Figure 5 is a perspective view of the moving parts of the device.

Figure 6 is a perspective view of a detail of structure.

The switch illustrated on the drawing comprises an escutcheon plate 10 which may be of any desired contour and of any suitable insulating material, preferably a moldable plastic. This plate is provided with suitable holes 12 to receive screws by which it can be secured to a supporting wall. On the front face of the plate 10 is an operating knob 20 which is slideable thereon to open and close the switch. The knob 20 is held in assembled relation with the plate 10 by suitable means such as a pair of posts 22 having heads embedded in the knob 20. These posts project rearwardly through corresponding slots 24 in the plate 10, the slots being elongated in the same direction so that the posts 22 can ride in the slots when the knob is moved from one position to another. As indicated in Figures 2 and 6, each of the slots 24 is enlarged near the rear face of the plate 10, forming an inner shoulder 26. Seated against each shoulder 26 is a metal grommet 30 which acts as a wear piece. The projecting end portions of the posts 22 are expanded as at 32 after the posts have been in-

serted through the narrow portions of the slots 24. The expanded end portions 32 overlap the wear pieces 30 so that the knob is thus held in assembled relation with the plate 10.

A pair of conductors 40 are embedded in and extend through the plate 10, each of these conductors presenting its forward end face 42 for contact with a bridging conductor 44. The bridging conductor may, as indicated in Figure 5, consist of a strip of metal, the ends of which are bent up at right angles to the main portion of the conductor, the bent-up end portions 46 projecting into a pair of recesses 48 formed in the rear face of the knob 20 when the same is molded. At the same time a central recess 50 is formed in the knob between the recesses 48, these recesses being connected by a shallow channel 52 for the main portion of the bridging conductor 44. The central recess 50 receives a compression spring 54, one end of which is adapted to bear against the central portion of the bridging conductor 44 when the end portions 46 are disposed within the end recesses 48. The member 44 is provided with a pair of small bulges 56 which are arranged to make simultaneous contact with respective conductors 40. The forward end faces 42 of these conductors are preferably countersunk or hollowed as indicated in Figure 3, so that the bulges 56 may ride into and out of these hollows, thus holding the switch yieldably in closed position. The spring 54 presses the member 44 constantly toward the rear so that the bulges 56 are always in firm contact with some portion of the plate 10 or the forward ends 42 of the conductors 40.

Projecting rearwardly from the back of the plate 10 are a pair of elements 60 which are binding posts or the equivalent thereto. These elements are either integral with or electrically connected to respective conductors 40, so that circuit wires may be connected to the elements 60 to connect the switch into an electric circuit. The front face of the plate 10 may be provided with a tell-tale spot 62 in the form of a small indentation containing pigment which is covered by an end of the knob 20 when the switch is open and which is exposed when the knob is moved to close the switch.

It is evident that various modifications and changes may be made in the embodiment of the invention herein shown and described without departing from the spirit or scope of the invention as defined in the following claims.

I claim:

1. An electric switch comprising an escutcheon

- plate of insulating material, a pair of conductors extending through the escutcheon from the front face to the rear face thereof, an operating knob slidable on the front face of said escutcheon, a bridging conductor movable by and with said knob on the face of the escutcheon to and from a closed switch position in contact with both of said pair of conductors, and means holding said knob and escutcheon in assembled relation.
10. An electric switch comprising an escutcheon plate of insulating material having a pair of slots therethrough elongated in the same direction, a pair of conductors each having a portion embedded in said plate so as to present a contact surface at the front face of the plate and a portion projecting from the rear face of the plate to serve as a binding post, an operating knob of insulating material slidable on the front face of said plate and having recesses in its rear face, a bridging conductor and a spring in said recesses arranged so that the spring presses the bridging conductor rearwardly against the front face of the plate, and a pair of posts projecting rearwardly from said knob through said slots, respectively, the ends of said posts being enlarged to hold said knob in assembled relation with said plate.
15. An electric switch comprising an escutcheon plate of molded plastic material with a pair of slots therethrough, each slot having a greater width at the rear face of the plate than at the front face with a shoulder within the plate on each side of said slot, grommets seated on said shoulders, an operating knob of molded plastic material slidable on the front face of said plate, a pair of conductors embedded in said plate so that portions thereof are exposed at the front face of the plate for contact, a bridging conductor movable by and with said knob into contact with both of said pair of conductors, and means for maintaining said knob and plate in assembled relation, said means including a pair of posts projecting rearwardly from said knob into respective slots, the end of each post being enlarged to overlap said grommets.
20. An electric switch comprising an escutcheon plate of insulating material, a pair of conductors extending through said plate and exposed at the front face thereof for contact, a knob of insulating material slidable a limited distance on the front face of said plate, a bridging conductor movable by and with said knob into and out of simultaneous contact with the exposed portions of said conductors, and means for maintaining said knob and plate in assembled relation, said knob being arranged to permanently conceal all of said conductors and said means.
25. An electric switch structure comprising an escutcheon plate, electric terminal members fixed directly to said plate, a button slidable relative to said plate, a contact member resiliently mounted within said button for completing the circuit between said terminals when the button is in one position, and means for slidably mounting said button directly on said plate, said last-named means including members fixed to said button and extending through said plate, said last-named members being bent to slidably engage said plate for slidably mounting said button relative to the escutcheon plate.
30. An electric switch structure comprising an escutcheon plate, electric terminal members fixed directly to said plate, said escutcheon plate having elongated substantially parallel recesses formed in the rear face thereof, a slide plate disposed within each of said recesses, a button on the forward face of said escutcheon plate slidable relative thereto, a contact member resiliently mounted within said button for completing the circuit between said terminals when the button is in one position, and the means for slidably mounting said button directly on said escutcheon plate, said last-named means including members fixed to said button and extending through said escutcheon plate adjacent said slide plates, said last-named members being bent to slidably engage said slide plates for slidably mounting said button relative to the escutcheon plate.
35. An electric switch comprising an escutcheon plate having a slot therethrough, a pair of conductors each mounted on said plate so as to present a contact surface flush with the front face of the plate and to project rearwardly from the plate to serve as a terminal, an operating knob slidable on the front face of the plate and having a recess in its rear face, a bridging conductor disposed in said recess and movable by said knob into and out of simultaneous contact with said pair of conductors, a spring in said recess arranged to press said bridging conductor against the front face of said plate, said pair of conductors being insulated from one another when the switch is open, and means for maintaining said knob in assembled relation with the plate, said means including an element projecting through said slot and bearing against the rear of the plate.
40. An electric switch comprising an escutcheon plate of insulating material having a pair of slots therethrough elongated in the same direction, a pair of conductors each having a portion embedded in said plate so as to present a contact surface at the front face of said plate and a portion projecting from the rear face of the plate to serve as a terminal, an operating knob of insulating material slidable on the front face of said plate and having a recess in its rear face, a bridging conductor in said recess movable by said knob into and out of simultaneous contact with said pair of conductors, a spring in said recess arranged to press said bridging conductor against said plate, and means for maintaining said knob in assembled relation with said plate, said means including a pair of elements projecting through respective said slots and having portions bearing against the rear of the plate.

HUGH W. BATCHELLER.
